UNITED STATES PATENT OFFICE.

JAMES W. BARSANTEE, OF EAST SOMERVILLE, MASSACHUSETTS.

IMPROVEMENT IN REAMERS FOR METAL.

Specification forming part of Letters Patent No. **146,637**, dated January 20, 1874; application filed November 14, 1873.

To all whom it may concern:

Be it known that I, JAMES W. BARSANTEE, of East Somerville, in the county of Middlesex and in the State of Massachusetts, have invented certain new and useful Improvements in Reamers; and do hereby declare that the following is a full, clear, and exact description thereof, reference being had to the accompanying drawing making a part of this specification, in which—

Figure 1 is a perspective view of my improved reamer as arranged for use. Fig. 2 is a like view of the several parts composing said reamer, separated from each other, and Fig. 3 is a central longitudinal section upon line *xx* of Fig. 1.

Letters of like name and kind refer to like parts in each of the figures.

The design of my invention is to enable the diameter of a reamer to be increased or diminished, so as to compensate for wear, or to vary the dimensions of the openings that said reamer is capable of making; to which end it consists in the construction and combination of the several parts of the device, substantially as and for the purpose hereinafter set forth.

In the annexed drawing, A represents a reamer, having exteriorly a round form, and fluted upon its periphery, so as to produce a series of longitudinal cutting-faces, *a*, of usual form. Passing through the center, longitudinally, of the reamer A is a round opening, A', which has a slightly larger size at the upper end of said reamer, while, from said opening, two or more slots, *a'*, extend radially outward to the bottoms of the grooves that form the cutting-faces *a*, said slots having, longitudinally, such length as to bring their ends within, but near, the ends of said reamer. Within the opening A' is fitted a spindle or mandrel, B, which has a tapering exterior, that corresponds exactly to the size and shape of said opening, and, when pressed longitudinally through the same, expands the slotted portion of the hollow reamer in proportion to the degree of motion and the amount of taper given to the bearing-surfaces. The longitudinal position of the hollow reamer upon the mandrel is insured by means of two nuts, C and D, the first of which is placed upon a correspondingly-threaded portion, *b*, of said mandrel, and bears against the upper end of said reamer, while the second nut is placed upon the lower threaded end *b'* of said mandrel, and bears

against the corresponding end of said reamer. In order that motion of the reamer around the mandrel shall not loosen the nuts, the upper thread, *b*, is given a left-hand turn, and the lower thread, *b'*, a right-hand turn, so as to cause said nuts, when rotated by contact with the ends of said reamer, to move longitudinally inward and bind more closely upon said ends.

As a further means for accomplishing such object, the lower end of the reamer A and the upper end of the nut D are correspondingly cut away, as shown, so as to cause the projecting portion of the former, *a''*, to engage with the notch *d* of the latter, and lock said parts together after the manner of a clutch. As thus combined, the reamer and lower nut can only move together around the mandrel, so that any motion of said reamer away from its cut will cause said nut to press it more firmly against the upper nut until further motion is rendered impossible.

The device thus constructed enables holes to be reamed out with the greatest nicety, and shades of difference made in size that would be impracticable to reamers of ordinary construction.

In addition to these advantages, the reduction in size of the reamer occasioned by wear and by dressing the cutting-faces can be compensated for, so as thereby to materially increase the usefulness of the tool. If desired, one mandrel can be used in connection with a number of reamers having different sizes, and thereby the cost of the set materially reduced.

Having thus fully set forth the nature and merits of my invention, what I claim as new is—

The reamer A, provided with the cutting faces *a*, the central opening A', and the longitudinal radial slots *a'*, the arbor or mandrel B, provided with the threaded portions *b* and *b'*, and the nuts C and D, when said parts are constructed and combined to operate in the manner and for the purpose substantially as set forth.

In testimony that I claim the foregoing I have hereunto set my hand this 10th day of November, 1873.

JAMES W. BARSANTEE.
